(57) **CLAIM**

The ornamental design for a hair curler, as shown and described.

DESCRIPTION

FIG. 1 is a first perspective view of a first embodiment of a hair curler showing my new design;

FIG. 2 is a second perspective view thereof;

FIG. 3 is a front view thereof;

FIG. 4 is a back view thereof;

FIG. 5 is a left side view thereof;

FIG. 6 is a right side view thereof;

FIG. 7 is a top view thereof;

FIG. 8 is a bottom view thereof;

FIG. 9 is a first perspective view of a second embodiment of a hair curler showing my new design;

FIG. 10 is a second perspective view of the second embodiment thereof;

FIG. 11 is a front view thereof;

FIG. 12 is a back view thereof;

FIG. 13 is a left side view thereof;

FIG. 14 is a right side view thereof;

FIG. 15 is a top view thereof;

FIG. 16 is a bottom view thereof;

FIG. 17 is an enlarged view of portion "17" shown in FIG. 1;

FIG. 18 is an enlarged view of portion "18" shown in FIG. 1; and,

FIG. 19 is an enlarged view of portion "19" shown in FIG. 2.

(Continued)

The evenly-spaced broken lines illustrate portions of the hair curler and form no part of the claimed design. The dot-dash broken lines illustrate enlarged view indicators and form no part of the claimed design.

1 Claim, 19 Drawing Sheets
